ILLUMINABLE FLORAL CONTAINER OR SIMILAR ARTICLE

Fred W. Tredup, Chicago, Ill., assignor to A. L. Randall
Company, Chicago, Ill., a corporation of Illinois

Application January 3, 1955, Serial No. 33,786

Term of patent 3½ years

(Cl. D35—3)

FIG. 1

FIG. 3

Fig. 1 is a perspective view of the front of an illuminable floral container or similar article embodying my new design;

Fig. 2 is a perspective view of one side of the same;

Fig. 3 is a perspective view of the other side of the same; and

Fig. 4 is a top plan view of the same.

I claim:

The ornamental design for an illuminable floral container or similar article, substantially as shown.
